CLAIMThe ornamental design for a box extrusion, as shown
and described.**DESCRIPTION**FIG. 1 is a perspective view of a box extrusion showing
my new design;FIG. 2 is a right end elevational view thereof, the left
end elevational view being a mirror image thereof;

FIG. 3 is a front elevational view thereof;

FIG. 4 is a top plan view thereof;

FIG. 5 is a rear elevational view thereof; and,

FIG. 6 is a bottom plan view thereof.

A characteristic feature of the design of the box extrusion
is the extremely large height dimension in relation
to the width of the device, with a large closed box-like
member being the largest single segment, in terms of
area, of the device, the dimensions resulting in a vaulted
arch-like appearance.FIG-1

FIG-2

FIG-3

FIG-4
